NECKTIE

Montie M. Brohard, Jr., Norwood, Ohio

Application January 13, 1941, Serial No. 374,270

2 Claims (Cl. 2—146)

This invention relates to improvements in a necktie of the four-in-hand variety, and has as one of its objects the provision of a single pronounced dimple in the outer fabric of the tie directly beneath the knot.

Another object of the invention is to provide highly simplified and inexpensive means in a necktie construction, for establishment of a smooth and pronounced dimple of the character stated.

Another object is to accomplish the advantages mentioned without thickening the necktie, and without resorting to the use of extra layers and unusual types of material in the construction of the tie.

Another object of the invention is to include in the tie structure a simple and effective means incorporated in the lining, for causing the outer fabric to lay smooth within the limits of the knot.

The foregoing and other objects are attained by the means described herein and disclosed in the accompanying drawing in which:

Fig. 1 is a plan view of the knotted necktie, parts of the outer fabric being broken away.

Fig. 2 is a cross-sectional view taken on line 2—2 of Fig. 1.

Fig. 3 is a fragmental plan view of the tie lining per se.

In the past, various necktie structures were proposed for the establishment of one or more dimples or recesses in the outer fabric of a necktie below the knot. The proposals of the past, however, were highly unsatisfactory and impractical for various reasons, for example, in some of the proposed constructions it was necessary to make the lining highly special and of unusual materials for the purpose, such as rubber, which could not withstand cleaning and pressing without deterioration, or without giving off an objectionable odor. In other proposed structures, the results desired were accomplished by rigidifying portions of the necktie liner either by means of chemicals, or by the insertion of folds or laps which thicken the necktie at certain locations, with the objection that pressing resulted in the formation of objectionable creases, while at the same time the easy formation of a knot was interfered with. In every instance, the previously proposed structures were costly and added materially to the labor as well as to the amount of fabric required in the manufacture of the necktie.

All of the foregoing disadvantages have been obviated by means of the present invention, and

all of the advantages sought have been gained using greatly simplified and inexpensive means involving no resort to added material.

With reference to the accompanying drawing the character 4 indicates generally the body or outer fabric of the necktie, while 5 indicates the lining fabric which is substantially enveloped by the outer fabric. The body or outer fabric may be of standard or customary construction,

10 including a pointed end 6, hemmed and stitched as at 7 and 8 where necessary, the thickness of the body or outer fabric being indicated at 9 of Fig. 1. As is customary, the hemmed laps 10 and 12 are provided at the back of the tie, these 15 parts being overlapped as indicated at 13 and joined to the liner 5 by means of a loose slip stitching or basting thread or the like 14 applied through the overlap and the liner at widely spaced intervals to provide the long stitches 15. 20 The stitches 15 ordinarily will be repeated throughout substantially the length of the tie liner for retaining the liner in proper position with relation to the body of the tie.

As shown, the liner 5, which is made of ordinary coarse fabric cut on a true 45 degree bias, 25 is furnished with a longitudinal narrow slit 16 which lies along the center line of the fabric liner. The slit may be formed either by slicing through the liner with a single cut of a knife, or by actually removing a narrow section of the fabric at each side of the center line of the liner. The latter treatment is considered preferable as it more readily enforces the production of a pronounced dimple 17 beneath the knot 18 of 30 the tie. While the dimensions of the slit or slot may be somewhat altered within reasonable limits, it is found that maximum desirable results are obtained by making the slit or slot about one-quarter inch wide, and of a length approximating one-fifth the length of the liner, or about seven inches. The location of the aperture 16 is such that the major portion thereof will in the normal knotting of the necktie, be disposed beneath the knot and project directly toward the 35 pointed end of the tie body.

The production of the aperture 16 in the liner results in the formation of identical long narrow strips 19 and 20 of liner fabric, bounded by outer edges 21 and inner edges 22 equally spaced. For 40 accomplishing the best results, tension arresting means are incorporated in the strips 19 and 20, which arresting means in its simplest form may consist of the longitudinally disposed rows of stitching 23 and 24 located midway between the edges of the strips 19 and 20, respectively. Thus

the slit or aperture 16 is flanked at each side by a lining strip area and a tension arresting means, which are substantially coextensive with the length of the slit or aperture. The two longitudinal lines of stitching 23 and 24 perform to create opposing tensions in the lining, decreasing the degree of elasticity of the fabric strips 19 and 20 so that the fabric of the tie body which lies upon the stitched strips is induced to remain smooth and flat when the knot is formed, except at the location 17 where the tie body fabric falls into the slit or aperture 16 to form a long central dimple or concavity. An incidental function of the stitching lines 23-24 is to tie the short threads of the bias cut lining material forming the side strips 19 and 20. As shown in Fig. 3, the stitch lines may extend slightly above and below the extremities of the slit or aperture 16. A minor portion of the upper ends of the lines of stitching, as well as a minor portion of the upper end of the slit or aperture, may be included within the knot 18 without detracting from the tendency of the outer fabric to automatically or naturally fall into the aperture or slit 16 while concentrating every small wrinkle at the region of the aperture or slit so as to form one single elongated dimple in the exact center of the tie. It may be said that the outer tie fabric naturally follows the line of least resistance upon formation of the knot, by falling into the elongated aperture or slit, while the adjacent portions at opposed sides of the dimple remain supported by the stitched strips 19 and 20 which define the single central recession furnished by the slit or aperture 16. The tension arresting means incorporated in the instant construction do not noticeably add to the thickness of the tie, nor will they mark the outer fabric when the tie is pressed. If desired, the stitch lines 23 and 24 may be joined together at their ends by short transverse lines of stitching, without detracting from the intended functions of the parts. As previously stated, the liner need not be of special material, but may be formed from the usual coarse weave of fabric cut on the bias at substantially a 45 degree angle. Throughout the length of the tie, the liner is of a single thickness, and no special effort need be made to increase its rigidity or flexibility in order to enforce the production of the single central dimple at the front of the tie. In other words, the longitudinal strip regions 19 and 20 of the liner are equally as flexible as the remaining portions of the liner, although their liability to stretch may be somewhat limited by the tension arresting means indicated at 23 and 24.

As will readily be evident, the manufacturer of the improved tie of this invention may proceed in the customary manner to produce the body of the tie, the only change required being the formation of the slit or elongated aperture 16

along the center line of the liner, with the addition of elongated lines of stitching substantially bisecting the resultant strips 19 and 20 at the opposite sides of the slit or aperture. The production of the improved necktie is one of great simplicity in comparison with previously proposed structures, so that all the advantages of the earlier structures are retained while the disadvantages thereof are obviated. The ultimate result is that the art of manufacturing neckties of the four-in-hand variety has been simplified and at the same time advanced in the interest of enhancing the appearance and facilitating the proper formation of the knot.

What is claimed is:

1. A four-in-hand necktie constructed so as to present a central dimple directly beneath the knot when tied, comprising in combination an outer fabric envelope having a knot-forming area, and a stretchable liner of bias cut coarse woven fabric enclosed within said envelope, the liner including outer side edges and having a medial elongated aperture midway between said side edges in the region of the knot-forming area of the outer envelope, leaving narrow bias cut disintegrable strips of fabric flanking said aperture, and stretch arresting means carried by the liner at opposite sides of the single aperture in substantially coextensive relationship thereto, said stretch arresting means being in the form of long lines of stitching disposed in substantial parallelism with the major axis of the elongated aperture, serving also to bind the short threads of the aforesaid narrow strips of fabric which flank the aperture, thereby to preclude disintegration of the narrow strips by separation of their constituent short bias cut threads.

2. A four-in-hand necktie constructed so as to present a central dimple directly beneath the knot when tied, comprising in combination an outer fabric envelope having a knot-forming area, and a stretchable liner of bias cut coarse woven fabric enclosed within said envelope, the liner including outer side edges and having a medial elongated aperture midway between said side edges in the region of the knot-forming area of the outer envelope, leaving narrow bias cut disintegrable strips of fabric flanking said aperture, and stretch arresting means carried by the liner at opposite sides of the single aperture, said stretch arresting means being in the form of long lines of stitching disposed in substantial parallelism with the major axis of the elongated aperture in flanking relationship to said aperture, and extended beyond both ends of said aperture, the stitching being in binding relationship to the short biased threads of the narrow fabric strips to preclude disintegration of the strips by separation of their constituent short threads when the liner is subjected to tensile strains.
